Primary Examiner—James Gandy*Assistant Examiner*—Linda Brooks*Attorney, Agent, or Firm*—Stetina Brunda Garred & Brucker[57] **CLAIM**

The ornamental design for a storage rack, as shown and described.

DESCRIPTION

FIG. 1 is a front perspective view of the storage rack of the present invention showing our new design;

FIG. 2 is a top plan view thereof;

FIG. 3 is a front elevational view thereof;

FIG. 4 is a side elevational view thereof, the opposite side being a mirror image;

FIG. 5 is a front perspective view of a second embodiment of the storage rack of the present invention showing our new design;

FIG. 6 is a top plan view of FIG. 5;

FIG. 7 is a front elevational view of FIG. 5; and,

FIG. 8 is a side elevational view of FIG. 5, the opposite side being a mirror image.

The rear of the storage rack forms no part of the claimed design.
